UNITED STATES PATENT OFFICE

2,249,387

SPINDLE

Francis E. Kelley, Providence, R. I.

Application September 19, 1938, Serial No. 230,597

2 Claims. (Cl. 308—149)

This invention relates to spindles used in spinning and twisting operations.

It is the general object of my invention to provide a spindle so constructed that larger and heavier bobbins or spools may be run at higher speeds and with reduced vibration.

A further object is to provide a spindle in which the vibration due to an unbalanced load will be substantially decreased.

My invention further relates to arrangements and combinations of parts which will be herein-after described and more particularly pointed out in the appended claims.

A preferred form of the invention is shown in the drawing, in which

Fig. 1 is a sectional side elevation of my improved spindle;

Fig. 2 is a partial elevation, looking in the direction of the arrow 2 in Fig. 1; and

Fig. 3 is a sectional plan view, taken along the line 3—3 in Fig. 2.

Referring to the drawing, I have shown a twister spindle comprising a base 10 adapted to be clamped to a rail 11 by a nut 12, and a bearing bolster 15 supported therein and held from rotation by a key 16. A spindle blade 20 is provided with an upper ball bearing 21 mounted in the bolster 15 and also with a lower bearing 22 similarly mounted.

The usual whirl 24 is mounted on the blade 20 and is recessed to extend down over the upper end of the base 10 and bolster 15. The whirl 24 is thus adapted to be engaged by a driving belt in substantial alignment with the ball bearing 21.

The parts thus far described are of the usual construction and in themselves form no part of my present invention, which relates particularly to the manner of supporting a spool S on the blade 20.

For this purpose, I provide a sleeve 30 having a supporting member 31 fixed in its upper end and firmly secured on the reduced upper end 32 of the spindle blade 20. At its lower end, the sleeve 30 is provided with a flange or disc 35 having driving lugs 36. A metal cap 40 secured to the bottom of the spool S rests on the flange 35 and is slotted to receive the driving lugs 36.

It will be noted that the under side of the flange 35 is spaced from the top surface of the whirl 24, and also that the interior surface of the sleeve 30 is substantially spaced transversely from the blade 20, to which blade it is attached at its upper end only by the supporting member 31.

The weight of the spool and its load is thus supported entirely from the reduced upper end portion 32 of the blade 20. The upper portion

of the blade 20 also has sufficient resilience to permit the lower portion of the sleeve and spool to be yieldingly displaced transversely relative to the blade 20 and to its bearings.

5 The advantage of this construction lies in the fact that an unbalanced spool or a spool with an unbalanced load may self-adjust itself transversely relative to the spindle blade, thus centralizing the load on the spindle and preventing the excessive wear and pounding of the bearings which is commonly caused by rotation of unbalanced loads at the high speeds now prevalent.

While I have shown my invention embodied 15 in a certain form of twister spindle, it will be evident that the invention may be similarly applied to other forms of spinning and twisting spindles, as it is not dependent upon the detailed structure of the spindle but resides primarily in the provision of a load-supporting sleeve which is connected to the spindle blade at its upper end only and which is otherwise spaced from the blade and clear of the driving whirl.

Having thus described my invention and the 20 advantages thereof, I do not wish to be limited to the details herein disclosed, otherwise than as set forth in the claims, but what I claim is:

1. In a yarn producing machine, a spindle 25 having a blade which is slightly resilient in its upper portion, a driving whirl fixed to said blade, bearings for said blade positioned entirely below the point of attachment of said whirl to said blade, a load-carrying sleeve permanently fixed 30 to the extreme upper end portion only of said blade and elsewhere free and substantially spaced from said blade and said whirl, a spool-supporting flange fixed to the lower end of said sleeve but free from said blade and whirl, and means 35 on said flange to coact with and positively rotate a spool supported on said flange.

2. In a spindle assembly, a blade with a driving whirl fixed thereto, bearings for said blade positioned entirely below the point of attachment 40 of said whirl to said blade, a load-carrying sleeve fixed to the upper end portion only of said blade and elsewhere free and substantially spaced from said blade and said whirl, some portion of the blade above the point of attachment of the 45 whirl to the blade being of sufficient resiliency to permit the sleeve to be yieldingly displaced transversely relative to the blade and to its bearings during the operation of said spindle, a spool-supporting flange fixed to the lower end of said sleeve but free from said blade and whirl, and means 50 on said flange to coact with and positively rotate a spool supported on said flange.
